UNITED STATES PATENT OFFICE.

CALEB H. GRIFFIN, OF LYNN, MASSACHUSETTS, ASSIGNOR TO WALTER D. RICHARDS, OF SAME PLACE.

IMPROVED APPARATUS FOR GRINDING ORES AND AMALGAMATING THE PRECIOUS METALS.

Specification forming part of Letters Patent No. 35,980, dated July 22, 1862.

To all whom it may concern:

Be it known that I, CALEB H. GRIFFIN, of Lynn, in the county of Essex and Commonwealth of Massachusetts, have invented a certain new and useful Improvement in Machines for the Separation and Amalgamation of the Precious Metals from their Ores, of which the following is a full, clear, and exact description, reference being had to the accompanying drawings, making part of this specification, in which—

Figure 1 represents a view in perspective of an apparatus to which my improvements are applied; and Fig. 2, a vertical longitudinal section of the same, taken centrally through the machine. Fig. 3 represents a vertical transverse section through the cylinder detached from the machine to show its internal arrangements.

In practice it has been found that the ores from which the precious metals are to be abstracted after they have been pulverized in the ordinary way are still too coarse to obtain from them the fine particles of gold, and therefore have again to be subjected to a further process of grinding and rubbing to reduce them still finer before being subjected to the action of the mercury in the amalgamator, the two forming separate and distinct machines, and having no connection with each other, so as to form a continuous process, and therefore involve the necessity of many manipulations at the expence of time and much labor.

I am aware that machines have been constructed to effect both operations conjointly and simultaneously with the same means, but to such machines there are many and serious objections, as while they grind the ores, they at the same time flour the mercury, and in this way destroy its efficiency, as it renders it very difficult to form and collect the amalgam, it being so comminuted that a great portion would flow off in the washings or water as it passes from the machine with the sand, &c., thus losing the benefit of the effect intended to be produced. To obviate this difficulty and to insure a more thorough amalgamation of all the fine particles of gold with the mercury by the thorough pulverization, admixture, and incorporation of the ores containing the precious metals with the mercury, is the object of my invention; and it con-

sists in so constructing an apparatus as that it will not only reduce the ores to the necessary degree of fineness to detach and separate the precious metals from the mineral substances in which they are contained, and brighten the particles to render them extremely susceptible to the influence of the mercury, but will afterward so exhibit these ores diluted to a thin consistency with water to the mercury as to insure a thorough amalgamation of the gold and separation from all foreign matters, thereby procuring a greater yield by one simple direct process than has been heretofore practicable in this class of machine.

To enable others skilled in the art to make, construct, and use my invention, I will now proceed to describe its construction and operation in detail, here premising that the apparatus may be made of any materials suitable for the purpose.

The machine, as represented in the accompanying drawings, consists of a frame-work constituting an upper, A, and lower, B, on which are mounted and secured the operative parts of the machine. On the upper table, A, is secured a frame, C, of suitable form and strength for the support of the cast-iron cylinder D. This cylinder is open at both ends and provided with necks a and a', which form and act as journals, and rest in bearings b, formed in the upper ends of the frame C. The end of the neck a next the lower table is made to flare so as to form a discharge opening or mouth for the ore after it has been sufficiently ground and ready to be conducted to the amalgamating-tub. This end or opening of the cylinder—both being concentric—is made larger than the other or feed-opening, so that the material may be freely fed in at the one end and made to discharge at the other.

To the inner periphery, and at either end of the cylinder D, is arranged a standard, e, to the inner end of each of which, and concentric with the cylinder, are mounted and secured bearings for the support of a shaft, d, this shaft, for greater security and rigidity, being also supported in the upper end of a standard, e, which is secured at its lower end to the side of the frame c on the feed side of the cylinder D. On this shaft, at or near the center, or equidistant from the two ends of the cylinder D, is mounted a solid cast-iron guide-frame, f, of

rectangular form, and made with projecting lips at the ends on both sides of the shaft, between which work the sliding sides of the arms *g* of the rubbers *h*, of which there are two, one being attached to each arm by means of hinge-joints *i*. These slides and arms may be cast in one piece and connected together at top by bands or plates of metal suitably shaped for that purpose, they being so shaped at their upper ends as to conform to the shape of the guide-frames.

In order to impart rigidity and strength to the arms *g*, stays *j* are cast or otherwise secured to each arm, they being further strengthened by being connected together on the under side of the shaft by an iron bar or plate, *k*, one end of which is firmly bolted to each, but at such distance from the shaft *d* and lower edge or side of the guide-frame *f* as will admit of the adjustment of the arms for the purpose of raising or lowering the rubbers *h* to regulate the distance between the hinged end of the latter and the inner periphery of the cylinder. This adjustment is effected by means of the screw *l*, the thread of which takes into a female screw cut in a collar formed on the upper connecting bands or plates of the arms *g*, while its lower end rests on the shaft *d*, passing freely through an opening without touching it, formed in the upper part of the guide-frame *f*, or it may be made to rest on the top of the guide-frame *f*, as may be deemed most advisable, or in any other well-known manner. With such an arrangement, by the simple turning of the screws in the direction required, the arms can be raised or lowered to regulate the distance between the ends of the rubbers *h*, directly attached to them, and the inner periphery of the cylinder. By this arrangement of the rubbers, although the bearings that support the shaft *d* are secured to the cylinder, it will be seen that the rubbers *h*, by virtue of their own gravity, will tend to remain in a vertical position and in a measure stationary, while the cylinder is left free to be rotated as rapidly as may be required for the thorough pulverization of the ores as the latter are made to pass between the rubbers and cylinder. In this case two rubbers are used; but one only may be used if deemed desirable, and these may be removed and heavier or lighter ones used, as the nature of the materials to be acted upon may require. Or, instead of the rubbers being hinged at one end to the arms, they may be rigidly secured, and adjusted in the same way to impart any required degree of fineness to the materials to be ground. In this connection it is proper to state that motion is communicated to the cylinder *D* from a belt passing around its outer periphery and the driving-wheel of some prime motor.

Immediately under the discharge opening or mouth *a* of the cylinder is arranged and secured to that side of the frame *c* a hopper, *E*, into which the pulverized and brightened material is discharged. To the lower end of this hopper is secured in any suitable manner

a spout, *F*, that conducts it to a funnel-shaped basin, *G*, which forms the mouth of the hollow shaft *H*, down and through which the material is conducted to the lower or amalgamating tub *I*, and there subjected to the action of the mercury. The basin *G* is formed in two parts, the inner one, *G'*, of which is shaped like an inverted hollow cone, without an opening at the bottom, and is supported by arms attached to its upper edge on the inside of the outer basin, *G*, fitting in lips formed on the latter to prevent its being whirled around with a motion independent of the motion of the basin *G*; or it may be secured in any other suitable manner, rigidly or otherwise. Into the inner basin, *G'*, the material from the spout is first discharged, whence it is discharged without being full and made to overflow into the outer basin, *G*, by the centrifugal force generated from the rotation of the shaft *H* and the outer basin, to the latter of which it is attached, as just described. These two basins *G* and *G'* are both galvanized or coated with mercury, well brightened and polished on their inner surface, and the inner one, *G'*, on its outer surface also, so as to attract such particles of fine gold as may be flowing directly over them on their passage toward the amalgamating-tub *I*. By making the inner basin removable it can be taken out when it becomes coated with gold or its amalgam to have the gold removed as well from it as the inside of the outer basin, *G*. In the same way and for the same purpose the amalgamating-tub *I* may also be coated with mercury and brightly polished, and the gold amalgam removed therefrom when sufficiently coated.

On the lower end of the hollow shaft *H*, and which is supported in bearings formed in a removable double cross-beam, *J*, attached to the outer edge of the upper end of the tub *I* in any suitable manner, are secured three disks, *m*, *n*, and *o*, the one above the other and at short distances apart, the uppermost (*m*) and largest and lowest (*o*) and smallest of which are provided with curved or straight radiating arms *s* on their under side, for the purpose of forcing out the water-diluted ore and mixing it with the quicksilver after its passage down through the hollow shaft, the whole of the disks for this purpose and the wings on the upper being entirely submerged beneath and among the mercury contained in the bottom of the tub *I*. The middle disk, *n*, consists of a perforated disk or wire-gauze properly strengthened with arms on its upper side, so as to mix the ore more thoroughly with the mercury by causing it to pass through its openings or meshes in fine streams, and thus not only retard but prevent its passage upward in a body. On the upper side of the disk *m* are secured arms or wings *p* for still further continuing the mixing process of the ore and mercury. Motion is communicated to these disks as armed through the shaft *H* by means of a pulley, *M*, keyed fast to the latter, round which passes a belt from the driv-

ing-wheel of the engine, the basins G and G' receiving at the same time and from the same source a revolving motion for the purpose of retarding, spreading, and attenuating the diluted ore over their mercurially-galvanized surface.

The operation is as follows: The mercury is first placed in the tub I to a depth sufficient to submerge the disks m, n, and o and arms p, and, if necessary, some inches above the latter, after which, and motion being communicated as well to the cylinder D as the hollow shaft H of the amalgamating-tub I, the ore (in a powdered condition from some other pulverizing-machine, but requiring to be still further reduced or comminuted and mixed with water to a thin consistency) is then fed slowly into the cylinder D through the feed-opening at the neck a', and there subjected to the grinding and rubbing action of the cylinder and rubbers h, passing during this action from the feed end of the cylinder to its discharge end, where it flows over and falls into the hopper chamber or mouth E of the spout F, and thence through the latter discharged into the inner cone-shaped basin G', whence it is again discharged by centrifugal force resulting from the rotation of the latter into the funnel or mouth G of the hollow shaft H, down and through which it is conducted to within a short distance of the bottom of the tub and beneath the mercury, where it is discharged by hydrostatic pressure and the aid of the arms s on the lower disk, o, which, being rapidly rotated by centrifugal force, force it outward through the mercury to the outer periphery of that disk. At this stage of the operation, the specific gravity of the ore and water being much less than that of the mercury, they are forced upward by the latter through the openings of the perforated plate or disk or meshes of the wire-gauze n in fine streams, and thus thoroughly mixed and incorporated with the mercury. Still ascending, they come within the sphere of action of the arms s, secured to the lower side of the upper disk, m, and by them forced out toward the inner periphery of the tub, between which and edge of the disk m they escape above, but still through the mercury, and are again subjected to the agitating and mixing influences of the wings or arms p, secured on the upper side of the disk m, until they are finally ejected from the mercury, leaving behind the precious metals in an amalgamated condition with the mercury. As the

water and dirt (powdered ores, &c.) accumulate in the tub above the mercury, they are allowed to pass off through openings or cocks, suitably arranged in the sides for that purpose, as rapidly as they accumulate, care being taken not to arrange them too high above the upper surface of the mercury, because of the increased resistance that would flow from their accumulation to the descent of the ore and water through the hollow shaft, unless the latter was correspondingly elongated. By this method of submitting the ores containing precious metals to the mercury they are subjected to a more thorough search than has been heretofore practicable, and enable me to obtain a much larger percentage of them from the same ore.

This apparatus may be used either in connection with cold water as the menstruum or diluent of the ore, or with boiling, for which purpose a furnace or steam may be used for imparting the heat, a particular description of which it is not deemed necessary to give, as it forms no part of my present invention, and here intended to be patented.

Having thus described my invention, what I claim as new, and desire to secure by Letters Patent, is—

1. The combination of the rotating cylinder D with the adjustable swinging rubber h, both being arranged, constructed, and operated in the manner substantially as and for the purposes described.

2. In connection with these the hopper E and spout F, the double funnel-shaped basins G and G', hollow shaft H, disks m, n, and o, as provided with arms s and p, and tub I, the whole being arranged, constructed, and operated in the manner substantially as and for the purposes set forth.

3. In combination with the basins G and G', or their equivalents, and hollow shaft H, through which the ores to be amalgamated are passed and fed into the mercury, the arrangement of a series of disks, m, n, and o, the upper and lower ones of which are provided with arms or stirrers and the middle one with perforations, the whole being submerged in mercury, and operating in the manner substantially as and for the purposes set forth.

In witness whereof I have hereunto set my hand this 1st day of May, A. D. 1862.

C. H. GRIFFIN.
